UNITED STATES PATENT OFFICE.

DARIUS D. LESTER, OF ROANOKE, VIRGINIA.

ROTARY ENGINE.

1,147,330.

Specification of Letters Patent. Patented July 20, 1915.

Application filed March 10, 1915. Serial No. 13,369.

To all whom it may concern:

Be it known that I, DARIUS D. LESTER, a citizen of the United States, residing at Roanoke, in the county of Roanoke and 5 State of Virginia, have invented certain new and useful Improvements in Rotary Engines, of which the following is a specification.

This invention pertains to fluid driven, 10 rotary engines, and among the objects thereof are the following: 1st:—To provide an improved form of sliding abutment for the reaction of the driving fluid. 2nd:—To provide a form of rotor peculiarly adapted for 15 use with my improved form of abutment. 3rd—To provide improved methods of forming the rotor so as to minimize the leakage of fluid around the piston and disk thereof. 4th:—To provide an improved form of pack- 20 ing ring for use with the revolving piston of my engine. 5th:—To provide improvements in abutment actuating means.

Other objects both apart from and in conjunction with the foregoing objects will 25 hereinafter appear as the description of my invention is set forth.

With such objects in view, the invention consists in the formation, combination and arrangement of elements as herein described 30 and particularly pointed out in the appended claims.

In the drawings which form a part of these specifications, Figure 1 is a side elevation of a rotary engine embodying the features of my invention and Fig. 2 an end elevation of the same. Fig. 3 is a section showing the abutment actuating piston, the same being taken on the line AB, Fig. 1. Fig. 4 is a sectional elevation of the assembled ma- 35 chine, taken on the line CD of Fig. 2. Fig. 40 5 is a horizontal section taken on the line EF, Fig. 4, a portion of the yoke guides being shown as broken away because of lack of space. Fig. 6 is a partial plan view, 45 showing the yoke guides and springs for which there was not space in Fig. 5. Fig. 7 is a section taken on the line GH, Fig. 4 through the rotor of my invention, showing the peculiar piston and rotor packings of my 50 invention. Fig. 8 is a diagrammatical view or the rotor of the machine showing the relative dispositions of the packing strips of the rotor and casing.

Referring now to these drawings wherein 55 like parts are similarly designated wherever

they occur, 1 represents the rotary engine as a whole, it being composed primarily of a casing 2, made up of the halves 3 and 4, a shaft 5 and a rotor 6 carried by the said shaft.

The casing 2 is provided with journals 7 and 8 for the shaft 5 and the halves 3 and 4 of the casing have spaced relation, longitudinally of the shaft with each other. The intervening space 9 between these parts of the casing is a radially converging space, and snugly occupying this space is the radially tapered rotor 6, the central portion 10 thus constituting an outwardly tapered disk, with the outer periphery rounded off as at 54. Concentric with the said shaft and rotor 1 provide an annular piston-way 11 and attached to the outer periphery of the rotor disk 10 is a revolute piston 12, the same being adapted to register with and be rev- 70 olubly accommodated by the said piston-way. This piston-way and the piston in it are made circular in cross section for the purpose of admitting the use of a modification of the ordinary circular, piston packing rings such as I have designated 13. As the piston 12 revolves in the piston-way 11 the packing rings 13 provide means for preventing the leakage of the driving fluid around the cylindrical piston proper. How- 75 ever, as the rotor revolves at high speeds it will be seen that the effect of centrifugal force would be to spread the open bottom of these rings and consequently throw them out of their true circular form and bearing. To 80 prevent this I provide these rings with the inwardly disposed dowels 14 and in the piston 12 I provide suitable registering holes 15 which receive these dowels and thereby retain the said rings in position on the revolv- 85 ing piston.

In engines of this type it is customary to admit the driving fluid against the back face 46 of the revolving piston and interpose a suitable fluid abutment across the piston-way, which serves as a reaction point for the fluid pressure and prevents the fluid from escaping to the atmosphere through the ex- 90 haust port.

With the engine rotating in the direction 105 of the arrows in Figs. 1 and 4 and referring particularly to Fig. 4, the driving fluid is admitted through the port 16 and it will be assumed that the abutment 17 is in the position across the piston-way as shown. The 110

pressure of the steam on other fluid against the face 46 of the piston will cause it to revolve in the piston-way and rotate the shaft 5. At the same time fluid on the opposite 5 side of the piston, or between the piston and the abutment 17 is being expelled through the exhaust port 18 to the atmosphere. As the piston 12 approaches the abutment 17, the latter is withdrawn from across the piston 10 ton-way to admit the passage of the piston and is then again interposed across the same and the driving fluid again admitted behind the said piston.

The general operation of such engines 15 having been explained, it is now among the provinces of my invention to form this fluid abutment in an improved manner and to provide improved means for actuating the same.

Extending preferably radially from the piston-way 11 I provide a recess 19 adapted 20 to accommodate the abutment 17 when withdrawn. The inner end 20 of the abutment is made preferably of Babbitt or other metal 25 capable of becoming slightly plastic under the influence of steam and capable of a certain amount of flow under pressure at low temperatures, and it is provided with a tapered and rounded groove 21 which coincides 30 with the taper of the disk portion 10 of the rotor and with the rounded periphery 54 thereof.

The tapered shape of the rotor disk with its rounded periphery provides a shape suitable 35 for the continued accommodation of the wearing end of the abutment as the wear advances it radially inward and leaves no sharp corners to wear into the abutment.

The recess 19 is provided at its outer end 40 with the pierced head 22 through which extends the outer end of the abutment 17.

External of the recess the abutment is provided with an extension or stem 23 and slidably accommodated upon this extension 45 is the cross bar or yoke 24. The nuts 47 serve to retain this yoke on the extension 23 and between the yoke 24 and the outer end 48 of the abutment is a leaf spring 25 which serves to form a yielding connection between 50 the abutment and its actuating mechanism.

The yoke 24 is provided with the holes 49 at the ends which slidingly engage the parallel guides 39. These guides are secured at their inner ends to the head 22 and at their 55 outer ends are provided with nuts 50. Occupying the space between these nuts 50 and the yoke 24 and encircling the guides 39 are compression springs 38, and it will be seen that these coil springs serve to keep the 60 inner end 20 of the abutment in intimate contact with the rotor disk and its periphery when the abutment is interposed across the piston-way, and the abutment thus forms a packing for the revolving rotor disk as well 65 as a fluid abutment across the piston-way.

The inner end 20 of the abutment does not extend entirely to the shaft 5 and to complete the packing radially of the space between the rotor disk, and the casing I provide packing strips 26 in suitable grooves 27 70 in the casing wall. These packing strips extend substantially radially from adjacent the shaft 5 to a point where they will be engaged by the inner end of the abutment 17 when it is interposed across the piston-way and the 75 inner end of the abutment is provided with suitable grooves 51 to receive the same.

Back of the packing strips 26 I provide expanding springs 28 so as to keep the packing strip at all times pressed out firmly 80 against the adjacent side of the rotor disk. The grooves 27 are furthermore made slightly deeper at their inner ends than at their outer ends so that the tendency will be for the packing strips to be kept at all times 85 in intimate contact with the shaft 5 and form a packing for the same.

The abutment 17 and the packing strips 26 thus together form a complete radial fluid abutment, and it now remains to provide 90 similar means to minimize the leakage around the disk portion of the rotor at the moving or piston end of the fluid-pressure cavity. This I accomplish in a similar manner, by having the rotor disk made with 95 radial grooves 52 extending from the shaft (and slightly within this shaft also) at the center, to and slightly within the piston 12. Inserted in these grooves are packing strips 29, the same being expanded outwardly 100 against the inner faces of the casing by means of the springs 30. Thus I have completed the closure of the fluid passage around the piston to such an extent that but slight leakage will occur.

While I have described the packing strips 26 as being substantially radial, yet they are in reality offset slightly from a radial line as shown in Fig. 8, so that in revolving the strip 26 will first touch the strip 29 at one of 110 its corners and the strips will thereby be enabled to readily pass one another. It will be seen that the strips 29 fall on the radial line JK while the strips 26 are disposed parallel to the radial line LM, so that the 115 strips first contact each other at their inner corners at 55.

It will be seen that the springs 38 will serve to always return the abutment 17 to its interposed position. But in order to 120 make this action more positive and instantaneous and at the same time to better regulate the fluid supply I provide the following means for effecting these combined results.

At 31 is a fluid distributing valve of any 125 approved form with the fluid supply connected thereto at 32. This valve has operative connection with the engine shaft and is shown in a position where it is admitting the operating fluid to the piston-way through 130

the ports 33, the passage way 56, the piston way 53 and the port 16 to the annular piston-way 11.

Inserted into the abutment 17 and extending slightly therefrom is a leaf or piston 34. This piston is accommodated by the upper portion 53 of the fluid passage-way and forms a closure across this passage-way. At 16 the passage-way 53 widens out as shown 10 and the fluid can now escape around the piston 34 and proceed to the annular piston-way 11. But previous to this it has served to augment the action of the springs 38 in quickly moving the abutment 17 inwardly. 15 Thus the admission of steam or other fluid above this piston portion of the abutment will tend to advance it across the annular piston-way and against the rotor disk, such advance, however, not being possible until 20 the cam 35 on the rotor shaft has turned to a correct position. This cam is so formed and disposed on the shaft that the operating stem 36 and roller 37 will be forced outwardly at predetermined periods, and the outer end of 25 the stem 36, abutting the yoke 24 will actuate the abutment 17, withdrawing the same from its position across the annular piston-way.

The stem 36 passes through suitable guiding holes 57 in the casing 4 and the head 22, and in order to prevent bending of this stem when the cam 35 is actuating it, the jaw portion 58 is restrained in suitable guides 59 cast out from the casing 4.

35 The yoke 24 is, as stated, yieldingly secured to the outer end of the abutment stem 23 and is prevented by any suitable means such as the guides 39 from turning out of registry with the abutting end of the stem 36.

40 When the cam 35 has revolved a suitable amount the roller 37 will follow down the reverse side 40 of the cam and the steam pressure above the piston portion 34 of the abutment 17, aided by the springs 25, will 45 advance the abutment to the position shown. When the piston 34 of the abutment has reached a point in its inward movement to open or uncover the port 16, the driving fluid will be admitted back of the piston 12, 50 and it will be seen that until the abutment 17 is almost seated against the rotor disk and across the piston-way, steam will not be admitted to the piston-way 11, hence 55 there is no possibility of the steam blowing past the abutment and out the exhaust port by premature admission. It will be seen that some clearance is allowed between the end of the stem 36 and the yoke 24 so that the springs 25 and the steam may be unhindered in holding the abutment against the disk, and the soft insert of the abutment 60 may wear down.

In order that there may be but slight clearance between the piston and the abutment just after the piston has passed, the

one face of the abutment at 41 is cut to an angular shape to more nearly conform to the face 15 of the piston as the abutment drops behind the same.

The abutment 17 is preferably made of 70 circular cross section so as the better to expand at its lower end under the influence of steam or pressure and of the tapered disk and for the purpose of forming a more desirable shape in the recess and through the 75 head 22.

In order to properly oil the revolving parts and particularly the disk portion of the rotor, I provide in the casing 3 an oil hole 42 and a threaded opening 43 for the attaching thereto any suitable form of oil cup or feed. The abutment 17 is likewise provided with an oil hole 44 and an oil passage-way 45 leading to the contact surface of the abutment. It will now be seen that whenever the abutment is withdrawn the hole 44 will momentarily register with the hole 42 and a charge of oil will be admitted to the passage-way 45 and the revolving parts will thereby receive their necessary oiling.

The means for operating the valve 31 from the engine shaft is not shown in the drawings as any approved reciprocating agent might be employed to accomplish this end.

Thus I have described the present embodiment of my invention. But I do not wish to be limited strictly to the construction shown and described, as various alterations might be made therein within the scope of the 100 claims without departing from the spirit of my invention.

Having thus described my invention, what I claim is:

1. In a rotary engine, a casing having an 105 annular piston-way therein, a concentric shaft journaled in said casing, a rotor secured to said shaft, said rotor comprising an outwardly and radially tapered disk having a piston secured to the outer periphery 110 thereof, the said piston being adapted to register with and be revolvably accommodated by the said annular piston-way, a fluid abutment for the said piston-way having radial operative relationship with the 115 said rotor, the said abutment being formed at its inner end of Babbitt or other soft metal and being adapted to inwardly and radially coat with the sides and the outer periphery of the said tapered disk of the 120 rotor to form a fluid closure, and means acting in timed relation to the rotation of the said rotor for alternately advancing the said abutment to and withdrawing the same from a position across the said piston-way 125 and in contact with the said disk.

2. In a rotary engine, a casing having an 130 annular piston-way therein, a concentric shaft journaled in said casing, a rotor secured to said shaft, said rotor comprising an

outwardly and radially tapered disk having a piston secured to the outer periphery thereof, the said piston being adapted to register with and be revolubly accommodated by the said annular piston-way, a fluid abutment for the said piston-way having radial operative relationship with the said rotor, the said abutment being formed at its inner end of Babbitt or other soft metal and being adapted to inwardly and radially co-act with the sides and the outer periphery of the said tapered disk of the rotor, means acting in timed relation to the rotation of said rotor for alternately advancing the said abutment to and withdrawing the same from a position across the said piston-way and in contact with the said disk, and a radially-outward extending recess from said piston-way adapted to receive and slidably accommodate the said abutment.

3. In a rotary engine, a casing having an annular piston-way therein, a concentric shaft journaled in said casing, a rotor secured to said shaft, said rotor comprising an outwardly and radially tapered disk having a piston secured to the outer periphery thereof, the said piston being adapted to register with and be revolubly accommodated by the said annular piston-way, a fluid abutment for the said piston-way having radial operative relationship with the said rotor, the said abutment being formed at its inner end of Babbitt or other soft metal and being adapted to inwardly and radially co-act with the sides and the outer periphery of the said tapered disk of the rotor to form a fluid closure, means acting in timed relation to the rotation of said rotor for alternately advancing the said abutment to and withdrawing the same from a position across the said piston-way and in contact with the said disk, the said means including an actuating rod and a yoke, the said yoke being yieldably connected to the said abutment.

4. In a rotary engine, a casing having an annular piston-way therein, a concentric shaft journaled in said casing, a rotor secured to said shaft, said rotor comprising an outwardly and radially tapered disk having a piston secured to the outer periphery thereof, the said piston being adapted to register with and be revolubly accommodated by the said annular piston-way, a fluid abutment for the said piston-way having radial operative relationship with the said rotor, the said abutment being circular in cross section and being formed at its inner end of Babbitt or other soft metal and being adapted to inwardly and radially co-act with the sides and the outer periphery of the said tapered disk of the rotor to form a fluid closure, means acting in timed relation to the rotation of the said rotor for alternately advancing the said abutment to and with-

drawing the same from a position across the said piston-way and in contact with the said disk, a radially-outward extending recess from said piston-way adapted to receive and slidably accommodate the said abutment, a fluid passageway in said recess and at the side of said abutment, and a lateral extension from said abutment forming a piston in the said fluid passageway, the said fluid passageway forming means for directing driving fluid from an external source to the said annular piston-way.

5. In a rotary engine, a shaft, a casing having an annular piston-way therein, a piston secured to said shaft and having revoluble relationship with the said piston-way, a sliding fluid abutment adapted to be alternately interposed and withdrawn from across the said piston-way in harmony with the revolutions of the said piston, a recess extending radially of said piston-way and across the same, and the said fluid abutment being slidably accommodated within the said recess, the said recess and abutment being circular in cross-section, and means for alternately withdrawing and interposing the said abutment across said annular piston-way, the said means comprising a cam mounted on the said shaft, an actuating stem adapted to be operated by the said cam, a yoke secured to said abutment and adapted to be outwardly actuated by the said actuating stem, and a spring adapted to inwardly actuate the said abutment.

6. In a rotary engine, a casing having an annular piston-way therein, a concentric shaft journaled in said casing, a rotor embodying a revoluble piston of circular cross section adapted to traverse the annular path of the said piston-way, the said piston being provided with annular packing rings and said rings being provided with inwardly disposed dowels at the sides thereof, and said piston being provided with holes adapted to receive the said dowels, the said dowels and holes constituting means for the retention of the said rings against centrifugal force.

7. In a rotary engine, a casing, the sides of which have spaced relationship with each other, the intervening space terminating at its outer periphery in an annular piston-way, a concentric shaft journaled in said casing, a rotor secured to said shaft, said rotor comprising a central disk portion having a piston secured to the outer periphery thereof, the said piston being adapted to register with and be revolubly accommodated by the said annular piston-way, and the said disk portion being rotatably positioned between the said sides of the casing, a radially disposed groove in the side of the said rotor extending from slightly within the said shaft radially across the said disk to and slightly within the said piston, a packing strip in the said groove, said pack-

ing strip extending for the full length of the said groove from within the said shaft at one end to within the said piston at the other end and being thereby retained within the said groove, and means for expanding the said packing strip from within the said groove to a position against the adjacent side of the said casing.

8. In a rotary engine, a casing, the sides 10 of which have spaced relationship with each other, the intervening space forming a circular fluid cavity and terminating at its outer periphery in an annular piston-way, a concentric shaft journaled in said casing, a 15 rotor secured to said shaft, said rotor comprising an outwardly and radially tapered disk having a piston secured to the outer periphery thereof, the said piston being adapted to register with and be revolubly accommodated by the said annular piston-way, a fluid 20 abutment across said piston-way having radial operative relationship with the said rotor, the said abutment being formed at its inner end to conform to and 25 to inwardly and radially co-act with the tapered disk portion of the said rotor, means acting in timed relation to the rotation of the said rotor for alternately advancing the said abutment to and withdrawing the same 30 from a position across the said piston-way, all in combination with a substantially radial groove in the inner side of the said casing and a packing strip in said groove, said packing strip being provided with 35 means for expanding the same laterally from said groove against the adjacent side of the said rotor disk and extending radially from adjacent the said shaft to adjacent the said piston-way, the said packing strip 40 being disposed circumferentially of the casing at a point adapted to be engaged by the said abutment when the same is advanced across the said piston-way, and means in said abutment for engaging the said packing strip.

Copies of this patent may be obtained for five cents each, by addressing the "Commissioner of Patents, Washington, D. C."

9. In a rotary engine, a casing having an annular piston-way therein, a concentric shaft journaled in said casing, a rotor secured to said shaft, said rotor comprising an outwardly and radially tapered disk having a piston secured to the outer periphery thereof, the said piston being adapted to register with and be revolubly accommodated by the said annular piston-way, a fluid abutment across said piston-way having radial operative relationship with the said rotor, the said abutment having a co-engaging groove in its inner end adapted to embrace the sides and outer periphery of the said rotor disk, and means acting in timed relation to the rotation of the said rotor for alternately advancing the said abutment to and withdrawing the same from a position across the said piston-way.

10. In a rotary engine, a casing having an annular piston-way therein, a shaft, a rotor carried by said shaft, a piston on said rotor adapted to register with and be accommodated by the said annular piston-way, a fluid abutment adapted to be interposed and withdrawn from a position across said annular piston-way and to have sliding contact with the said rotor and an oil hole 75 involved, a recess adapted to slidably accommodate the said abutment, an oil groove in the said abutment extending to its point of contact with the said rotor and an oil hole in the wall of the said recess, the said oil groove being adapted to register with the said oil hole when the said abutment is withdrawn and the said abutment being adapted to form a closure for the said oil hole when the said abutment is interposed, and a supply of oil connected to said oil hole.

In testimony whereof I affix my signature 85 in presence of two witnesses.

DARIUS D. LESTER.
